FRANK D. MAHONEY, OF SAN ANSELMO, CALIFORNIA

PORTABLE ELEVATOR

Application filed December 6, 1927. Serial No. 238,123.

This invention relates to improvements in elevators of the kind used to raise vehicles above the surface of floors.

An object of my invention is to provide an improved lifting device having means embodied therein for conveniently raising and maintaining a load above the surface of a floor.

Another object of my invention is to provide an improved lifting device for elevating loads which may be moved from place to place and suitably installed in different locations without damaging the floor construction upon which it rests.

Other objects more or less apparent will present themselves or will be specifically pointed out in the description to follow.

In the accompanying drawings:

Fig. 1 is a side elevation of a portable elevator embodying my invention, the dotted lines showing the position of the parts thereof when elevated;

Fig. 2 is a top plan view of a fragmentary part of the elevator;

Fig. 3 is an enlarged view taken on the line 3—3 of Fig. 1, certain parts being shown in cross section;

Fig. 4 is a sectional view taken on the line 4—4 of Fig. 3;

Fig. 5 is a sectional view taken on the line 5—5 of Fig. 1, the said view showing the device in an elevated position;

Fig. 6 is a sectional view taken on the line 6—6 of Fig. 5; and

Fig. 7 is a top plan view of an end of the elevator showing the construction and arrangement of the parts of the safety means.

Referring to the drawings, the numeral 1 represents a casing having a ram 2 movably located therein. A pipe 3 having a control valve 4 attached thereto is adapted to carry suitable quantities of compressed air or liquid to the casing for elevating the ram.

Securely attached to the top of the casing is

which are suitably secured as by welding to two upright supporting members 7. The supporting members 7 are secured at their lower ends to two horizontally disposed U-shaped channel bars 8, while two T-shaped and vertically disposed guide members 9 are secured as by welding to the inner surface of the said supporting members.

The upper end of the ram 2 is provided with an enlarged part 10 to which are secured the ends of substantially upright rods 11. The rods 11 movably extend through openings located in the plate 6 and are attached at their ends as by nuts to U-shaped members 12. Secured to the outer sides of the U-shaped members 12 are guides 13, the two outwardly disposed parts thereof being movably positioned around the inwardly projecting parts of the guide members 9.

Movably attached to the two downwardly disposed parts of each of the U-shaped members 12 as by pins which are secured to the said members, are rollers 14 or other slidale means which are adapted to support two horizontally disposed bars 15, that comprise a supporting frame for supporting a load placed thereon.

The channel bars 8 are each secured adjacent their ends as by welding or bolts to a plurality of transversely extending U-shaped supports 16 and 17 which serve to support and maintain the various parts of the device in their proper positions. The U-shaped supports 17 are separated from each other by predetermined intervening spaces, and each is provided intermediate its ends with a pair of upwardly extending U-shaped projections 18. Pivottally attached to each of the projections as by pins are lever arms 19, the opposite ends of which movably extend around transversely disposed rods 20. The rods 20 are suitably secured at their ends to the horizontally disposed bars 15.

Adjacent the ends of the channel bars 8 I have provided a safety means for maintain-

90

ing the horizontally disposed bars and the load in an elevated position, which is shown in detail in Figs. 1 and 7. The safety means comprises two bars 21 having teeth on their underneath edge, and said bars being pivotally attached to the channel bars 8 by pins or other suitable means. A pair of arms 22 are movably attached around the rod 20, and are provided at their opposite ends with outwardly projecting parts 23 which are adapted to move over and become lodged between the teeth of the bars 21 when the bars 15 are elevated. A pair of springs 24 attached to the ends of the bars 21 and the channel bars 8 serve to maintain the bars 21 in a downwardly disposed position until a lever rod 25 is moved upwardly against the said bars by pressing the foot pedal 26.

In operation a vehicle A or other load to be raised is placed over the bars 15, and suitable quantities of compressed air or liquid are allowed to pass into the casing 1 through the pipe 3. As the ram 2 is elevated by the compressed air or liquid passing into the casing, the rods 11 attached to the top of the ram pull the U-shaped members 12 in an upward direction, the guides 13 moving over the guide members 9 and maintaining the lifting parts of the apparatus in their proper operating positions. As the ram is elevated the rollers 14 moving in an upward direction with the U-shaped members 12, bring with them the two horizontally disposed bars 15, the latter as they are raised moving forwardly over the said rollers. The ends of bars 19 moving on their pivots, swing upwardly and support the bars 15 at different points thereon. The bars 15 with the load thereon may be maintained by the pressure of the compressed air or liquid in the casing 1 at any desired height, and the safety means by the engagement of the projections 23 with the teeth of the bars 22 may securely maintain the said load in an elevated position without danger of its falling. It is obvious to those skilled in the art that my invention may be embodied in other forms than the one illustrated, so for this and other reasons it is to be understood that the appended claims are to be considered as definitions of the limits my invention may assume.

Having described my invention what I claim is:

1. An elevator comprising a casing having a ram movably located therein, an upright rod attached at one end to the ram and provided with a roller at its other end, a horizontal bar supported by the roller and adapted to be raised and moved forwardly by the ram when elevated, and means for supporting the ends of the bar, whereby the bar may be maintained in a substantially horizontal position.

2. In an elevator, a casing having a ram movably located therein, a rod attached to

the ram, a bar carried by the rod, slidible means carried by the rod for allowing the bar to move forwardly when the ram is elevated, and means attached to the bar for supporting the same in a substantially horizontal position.

3. In an elevator, a casing having a ram movably located therein, a plurality of rods attached to the ram, a plurality of bars carried by the rods, slidible means carried by the rods for allowing the bars to move forward when the ram is elevated, and means for supporting the bars in substantially horizontal positions.

4. In an elevator, a casing having a ram movably located therein, supporting a frame carried by the ram, slidible means carried by the ram for allowing the frame to move forwardly when the ram is elevated, and means for supporting an end of the frame.

5. In an elevator, a casing having a ram movably located therein, a supporting frame, means connecting the frame and the ram, whereby the frame may be raised and lowered by the ram, rotatable means carried by the first mentioned means for allowing the frame to move forward when the ram is raised, and means for supporting an end of the frame.

6. In an elevator, a casing having a ram movably located therein, a plurality of upright rods secured at ends thereof to the ram, each of said rods being provided at its opposite end with a roller, a plurality of horizontal bars resting on the rollers and adapted to be raised and moved forward by the movement of the ram in an upward direction, and means movably attached to the bars for supporting the ends of the bars and maintaining the said bars in substantially horizontal positions.

7. In an elevator, a casing having a ram movably located therein, a plurality of upright members secured to the ram, guides attached to and coacting with the upright members for maintaining the members in upright positions, and a plurality of horizontally disposed bars movably supported by the upright members.

8. In an elevator, a casing having a ram movably located therein, a plurality of upright members secured to the ram, a plurality of horizontal bars carried by the upright members, means associated with the bars for maintaining them in a horizontal position and safety means for maintaining the bars in an elevated position when once they have been raised.

9. An elevator comprising a casing having a ram movably located therein, a plurality of upright members secured at ends thereof to the ram, each of said members being provided with a roller at its other end, a plurality of horizontal bars resting on the rollers and

adapted to be raised by the upward movement of the ram, and means pivotally attached to the bars and a base for supporting the ends thereof and moving them forward when they 5 are being elevated.

10. In an elevator, a ram, an upright member carried by the ram, a load supporting frame carried by the upright member, and a guide coacting with the upright member for 10 maintaining the upright member in a substantially vertical position.
